UNITED STATES PATENT OFFICE

CESAR LEANDRO VALDES Y VALDES, OF HABANA, CUBA

PACKING MACHINE

Application filed March 3, 1928. Serial No. 258,988.

This invention is directed generally to an improvement in cigarette packaging machines and particularly to a detail of such machine involving the feeding of the loose cigarettes from a container or hopper and the compressing of such cigarettes into uniformly sized arrangement to insure an accurate and proper cigarette mass to be presented to the wrapper, folding, and other succeeding elements of the packaging machine.

The invention has for its principal object the provision of means into which the cigarettes may be more or less loosely introduced from a hopper through a reciprocating feeder, and in which means the cigarettes are finally arranged and compressed into an accurately and proper sized package form for delivery to the subsequently operating mechanism of the packaging machine.

20 The invention is illustrated in the accompanying drawings, in which:

Figure 1 is a view in elevation of a conventional type of cigarette packaging machine with the improvements of this invention incorporated therein.

Figure 2 is a plan view of the same.

Figure 3 is an enlarged view in rear elevation of the compressing mechanism of this invention.

30 Figure 4 is a plan view of the same, the compressing mechanism being shown in normal position.

Figure 5 is a similar view with the compressing mechanism shown in operative position.

Figure 6 is a plan view showing the table of the compressing mechanism operated to permit bodily movement of the compressing mechanism while avoiding interference with 40 the plunger.

Figure 7 is a section on line 7—7 of Figure 3.

Figure 8 is a view similar to Figure 7 with the compressing mechanism in its lowered 45 position, that is, in a position to permit operation of the ejecting plunger.

Figure 9 is a section on line 9—9 of Figure 4.

Figure 10 is a section on line 10—10 of 50 Figure 3.

Figure 11 is a plan view of the cigarettes prior to their introduction into the compressing mechanism.

Figure 12 is a similar view of the cigarettes following their introduction into the compressing mechanism. 55

Figure 13 is a similar view of the cigarettes following the operation of the compressing mechanism.

The present invention is directed primarily 60 to means for compressing the cigarettes following their delivery from a hopper into a proper form or mass to be enclosed in a package or wrapper. The machine here illustrated in its entirety in Figures 1 and 2 is 65 shown primarily for the purpose of indicating the relative positions of the various essential elements of such a machine, it being understood that the parts of the wrapping or packaging machine proper which operate 70 upon the compressed block or mass of cigarettes after the compressive action of the details forming the subject-matter of this invention are substantially identical with the parts shown in my co-pending application 75 filed September 4, 1927, Serial No. 193,170, and as such details form no part of the present invention, no further specific description of the construction or operation of such parts is deemed necessary herein. 80

For the purpose of the present invention, the machine may be said to include a bed plate 1 supported on legs 2 on which is mounted a hopper 3 in the upper end of which the cigarettes are placed. The lower end of the hopper, which is substantially rectangular as at 4, is provided with a plurality of cells 5 into which the cigarettes group themselves in superimposed rows, so that at the lower end of the hopper the cigarettes are arranged in superimposed relation in transverse rows of the required number, say seven cigarettes, and disposed directly transverse the hopper. 85

The feeder 7 has spaced fingers 8 which, in the operation of the feeder, move through the cells of the hopper and push two rows of cigarettes through and beyond the hopper into the compression box to be later referred to. If desired and as preferred, a gate-like 95 100

member 6 may be provided at the feeder entrance side of the hopper to prevent the return movement of the feeder from moving the cigarettes outwardly.

5 The feeder is mounted upon a block 9 movable on guideways 10 supported above the bed plate by pedestals 11, the block being reciprocated by an arm 12 connected to the block by a link 13 and pivotally connected at its lower end at 14 to a cross bar 15 joining the legs. The arm 12 is longitudinally slotted at 16 to receive a pin 17 projecting eccentrically from a suitably driven disk 18 supported below the bed plate, so that in the 10 operation of the disk, the block 9 and thereby the feeder 7 is reciprocated relative to the hopper.

An ejecting plunger 19 is also secured to the block 9 below the feeder and operates entirely below the hopper, the operative end of the ejecting plunger having a cross bar or head 20 of a width and depth corresponding to the sectional area of the block or mass of cigarettes as finally compressed.

25 The compressing mechanism proper arranged immediately beyond the hopper in the direction of movement of the feeder includes a compression box 21 carried by rods 22 slidably mounted in sleeve-like bosses 23 secured to the bed plate 1, whereby the box is permitted a vertical reciprocating movement. This box has a hollow compression space 24 opening through the box in the longitudinal plane of the machine and defined by side walls 25, the bottom of the box having a lateral hollow depending portion 26 to permit movement of the plunger in a manner to be later described. This depending portion 26 of the box is connected through the medium of a rod 27 to suitable mechanism, not necessary to illustrate or describe, by which the box is given the necessary vertical reciprocating movement, as will be entirely obvious.

50 45 The floor of the compression space 24 is divided into a fixed section 28 integral with the box and a movable section 29 connected by a bar 30 and a link 31 to a lever 32 operated by appropriate parts of the power mechanism of the machine to cause the movable section to approach and recede from the fixed section of the floor at proper intervals.

55 A compression plate 33 is pivotally supported at 34 on one of the walls 25 of the compression box, the plate being pivoted at that end of the box in which the cigarettes are first introduced. The opposite end of the plate is provided intermediate the wall 25 and the plate with a spring 35 tending to hold the plate in divergent relation to the proximate wall of the box in the direction of cigarette feed when the box is free of cigarettes. The plate is provided with a limit pin 36 adapted to engage the proximate wall 60 65 25 of the box under that movement of the

plate tending to compressive action on the cigarettes, the limit pin serving to position the plate 33 in parallelism with the proximate wall of the box 25.

60 The opposite compression member is in the form of a plate 37 corresponding to the plate 33 and pivotally connected at 38 to a slide 39 which extends longitudinally of the compression space 24 in parallelism to the wall 25 of the box opposite that to which plate 33 is connected. The slide 39 is designed for operation in the compression space 24, being reciprocated transversely of said space. For this purpose the slide 39 is connected to or formed integral with a bar 39', provided at 75 its terminal with a pin 40 seating in a slot 41 in an upright 42 mounted on a plate 43 transversely slidable in a pedestal 44 fixed to the bed plate 1. The plate 43 is operated through the medium of an arm 45 actuated by an appropriate driving part of the mechanism. By this mounting, the compression box is permitted a vertical movement while at the same time the slide 39 may be reciprocated transverse the compression space 24.

85 90 The plate 37 is provided at its free end with an outwardly projecting pin 46 which, when the slide 39 is in inoperative position, as indicated in Figure 4, engages the end of the bar 30 connected to the movable bottom section 29 to thereby incline the plate 37 relative to the slide. Thus, the plates 33 and 37 normally converge in the direction of feed of the cigarettes and their entrant ends 47 may, if desired, be rounded to facilitate the entrance of the cigarettes.

95 100 The compression plates 33 and 37 act to compress the contained cigarettes on the sides of the mass, and while the bottom is confined by the floor sections 28 and 29, it is apparent that means must be provided for similarly confining the upper surface of the mass or block of cigarettes. The compression box is provided with a cover plate 48 removably secured by means indicated at 49, one of which may be in the form of a swinging latch member for more conveniently removing the plate. This cover plate overlying the compression space is formed with a transverse slot 50 in which is mounted a roller 51 rotating freely on a shaft 52 carried by brackets 53 arranged on the cover plate.

105 110 115 This roller 51 projects below the lower surface of the cover plate so that on introduction of the cigarettes, they will be guided by this roller in so far as the upper surface of the mass is concerned. Arms 54 are pivotally supported on uprights 55 rising from the bracket 53, which arms project laterally of the compression box and carry at their forward ends a freely rotatable compression roller 56 which operates through a slot 57 in the cover plate, the arms 54 above the roller being provided with a bridge rod 58.

120 125 130 With the parts arranged as described and

with the compression box in its uppermost or raised position, the feeder 7 advances through the cells 5 in the portion 4 of the hopper, pushes forward the requisite number of cigarettes and introduces them into the compression space 24. It is to be understood that the arrangement is such that the feeder pushes forward the cigarettes in two layers, with an appropriate number in each layer, and delivers them in this condition into the compression space. During this movement of the feeder, the plunger 19 also advances but passes into the open space of the portion 26 of the compression box. After the introduction of the cigarettes by the feeder, the feeder and plunger return to normal position and the compression box starts to move downwardly.

During this downward movement, the lever 45 is operated, the upright 42 advanced and the slide 39 moved toward the center of the compression space. This causes the compression plates 33 and 37 to compress the cigarettes into a proper area so far as the width of the mass is concerned while the roller 56 as well as the roller 52 serve to maintain the appropriate thickness of the cigarette mass. When the compression box has reached its lowest position, that is, in line with the head 20 of the plunger 19, the further movement of the feeder and plunger causes the plunger to first engage the formed cigarettes and advance them from the compression space into a wrapper delivered through a chute 59, which wrapper, as the advance continues, is folded into box form about the cigarette mass, as described in detail in the aforementioned application. As the plunger ejects the formed cigarettes from the compression space, the feeder is of course advancing to push forward a second mass of cigarettes for delivery to the compression space. Therefore, immediately following the delivery of the cigarettes from the compression space, the compression box starts to move upwardly to a position to receive the advancing feeder.

As the plunger is in the position occupied by the cigarettes in the compression space and as the compression box is rising, means must be provided to permit the box to avoid engagement with the plunger. This is accomplished through the then operation of the lever 32 which, through the bar 30, moves the movable section 29 of the floor of the compression box, so that the free edge of said movable floor section 29 is adjusted to a position sufficiently far from the free edge of the fixed floor section 28 as to provide an opening through which the bar 19 of the plunger may pass as the box rises. As the box moves to its upper limit or cigarette receiving position, the plunger has reached the opening in the depressed portion 26 of the box and the movable section of the floor is moved to closed position to receive the cigarettes.

The cigarettes as delivered by the feeder

are in the shape illustrated in Figure 11, that is, relatively spaced one from the other, and as they move in between the compression plates, when the latter are in the normal position as shown in Figure 4, they are brought closer together at their forward or advanced ends, as shown in Figure 12; the compact relation of the cigarettes after compression being indicated in Figure 13.

What I claim to be new is:

1. A cigarette compression means for use in connection with cigarette packaging machines, comprising a compression box mounted for vertical movement, feeding means for introducing cigarettes into the compression box when said box is at the upper limit of movement, a plunger for ejecting the compressed cigarettes from the box when the box is at its downward limit of movement, compression plates operating within the box to engage the sides of the cigarette mass, means operative during the downward movement of the box to actuate the compression plates relative to each other, and means operative during the upward movement of the box to provide an opening for the passage of the plunger to permit upward movement of the box while the plunger is in the advanced position.

2. A cigarette compression means for use in connection with a cigarette packaging machine, comprising a compression box mounted for vertical movement, said box being formed with a compression space opening through the box in the line of cigarette feed, a compression plate mounted adjacent one side of the compression space and normally inclined in the direction of cigarette feed, a second compression plate mounted in said compression space, a slide carrying said second compression plate, and means for operating the slide to move the second compression plate relative to the first mentioned compression plate to compress the cigarettes in said compression space.

3. A cigarette compression means for use in connection with a cigarette packaging machine, comprising a compression box mounted for vertical movement, said box being formed with a compression space opening through the box in the line of cigarette feed, a compression plate mounted adjacent one side of the compression space and normally inclined in the direction of cigarette feed, a second compression plate mounted in said compression space, a slide carrying said second compression plate, means for operating the slide to move the second compression plate relative to the first mentioned compression plate to compress the cigarettes in said compression space, a plunger operating through the compression space when the compression box is at its lowest point of movement, a floor for the compression space including a movable section, and means to

operate the movable floor section during the upward movement of the compression box to permit the relative passage of the plunger between the separated floor sections as the compression box rises.

4. Mechanism to form a package of cigarettes, which comprises a box provided with a movement of ascent and descent and maintained against a lateral movement by means of adequate guides, a compression member joined to the box and which is maintained in an inclined position by the elastic action of a spring while the cigarettes are introduced in the box, another compression member also arranged in an inclined position and joined to a movable member, which moves forward and backward in the interior of the box, approaching itself to the compression member first mentioned during the movement of descent of the box to compress between both the cigarettes which have been introduced in the box in the shape of a fan and to form with them an adequate package for the wrapping.

5. A mechanism to form a package of cigarettes, which comprises a box provided with a movement of ascent and descent and maintained against a lateral movement by adequate guides, receiving the cigarettes in the movement of ascent and compressing them on the descent, a compression member joined to one side of the box, a compression member jointed to a movable member which moves forward and backward in the interior of the box, said movable member being provided with a stem, a roller in the free end of said stem, which is lodged in the elongated groove provided in one piece, projecting from a plate which moves upon the adequate guides in such a manner that the forward advance of said plate imparts to said piece a similar movement which is transmitted to the stem from the movable member and to the compressor joined to the same, making them advance in the interior of the box while this one effects its movement of descent, to approach the other compression member and compress between both the cigarettes which have been introduced in the shape of a fan in the box and to form with them an adequate package for the wrapping.

6. A mechanism to form a package with a predetermined number of cigarettes, which comprises a box provided with the movements of ascent and descent and maintained against a lateral movement by means of adequate guides, said box being provided with a bottom divided into sections, one fixed and which form integral parts of the box and the other which moves upon adequate rollers separating itself, approaching itself to the fixed section and leaving between both a groove to permit the passing across it of the plunger which pushes forward the package of cigarettes and to extract it from the box while

this one is in its lowest position, in such a manner that the box may carry out its movement of ascent to receive a new supply of cigarettes without awaiting the backward movement of the plunger.

7. In machines to pack cigarettes, a mechanism to compress them and give them an adequate form to be wrapped, which comprises a box provided with compression members, a bottom divided into two sections, a top, grooves along the side of said top and next to its rearward and forward edges, in which are lodged cylinders whose peripheries protrude partially from the inner face of the top and which are raised by the contact with the cigarettes to enable the cigarettes of a diameter greater than the average to be easily introduced in the box without damaging them and which serve to prevent the cigarettes from falling toward the sides on being pushed by the compression member and thereby produce an imperfect package inadequate to be wrapped.

8. A mechanism to form a package with a predetermined number of cigarettes, constituted by a box which presents a bottom divided in two sections, one fixed and the other movable, means to drive the section of the movable bottom, a pair of compression members, one fixed and the other one movable, means to drive the movable compression member, a removable top provided with a groove close to its forward edge, a cylinder lodged in said groove whose periphery protrudes in part from the interior surface of the top, another groove close to its rear edge in which is lodged a cylinder whose periphery also protrudes partially from the inner face of said top, the cylinder being mounted upon a pair of oscillating arms so that it may be raised by the cigarettes upon cigarettes of larger diameter than the average being introduced into the box.

9. In a machine of the class described, a support, plates mounted thereon in spaced opposed relation to each other and between which articles to be packed are to be inserted in a bunch, means guiding the movement of said plates extending rearwardly thereof, and means yieldingly urging said first-mentioned means to cause the plates to normally assume positions in relatively diverging planes, said first-mentioned means being responsive to the insertion of a bunch of articles between the more widely spaced sides of the plates and subsequent movement therebetween to move the plates into positions substantially parallel to each other, whereby they will effect compression of the articles to compact, mutually contacting form.

In testimony whereof I affix my signature.
